[57] CLAIM

The ornamental design for a beverage can, as shown and described.

DESCRIPTION

FIG. 1 is a front elevational view of a beverage can showing our new design with a lip indentation recess;

FIG. 2 is a side elevational view of FIG. 1;

FIG. 3 is a rear elevational view thereof;

FIG. 4 is a top plan view of FIG. 2;

FIG. 5 is a bottom plan view thereof;

FIG. 6 is a front elevational view of a beverage can showing a second embodiment of our new design wherein the lip indentation recess is modified;

FIG. 7 is a side elevational view of modified form FIG. 6;

FIG. 8 is a rear elevational view thereof;

FIG. 9 is a top plan view of FIG. 7;

FIG. 10 is a bottom plan view thereof;

FIG. 11 is a front elevational view of a beverage can showing a third embodiment of our new design wherein the lip indentation recess is modified;

FIG. 12 is a side elevational view of modified form FIG. 11;

FIG. 13 is a rear elevational view thereof;

FIG. 14 is a top plan view of FIG. 12;

FIG. 15 is a bottom plan view thereof;

FIG. 16 is a front elevational view of a beverage can showing a forth embodiment of our new design wherein the lip indentation recess is modified;

FIG. 17 is a side elevational view of modified form FIG. 16;

FIG. 18 is a rear elevational view thereof;

FIG. 19 is a top plan view of FIG. 17; and

FIG. 20 is a bottom plan view thereof.
